ALBERT B. GULLY, OF BRIDGEPORT, CONNECTICUT, ASSIGNOR TO UNION METALLIC CARTRIDGE COMPANY, OF BRIDGEPORT, CONNECTICUT, A CORPORATION OF CONNECTICUT.

TARGET-BULLET.

1,122,738.

Specification of Letters Patent. Patented Dec. 29, 1914.

Application filed June 9, 1914. Serial No. 843,993.

To all whom it may concern:

Be it known that I, ALBERT B. GULLY, a citizen of the United States, residing at Bridgeport, county of Fairfield, State of Connecticut, have invented an Improvement in Target-Bullets, of which the following is a specification.

This invention has for its object to provide a non-jacketed bullet especially adapted for short range target shooting, which, owing to special details of construction hereinafter to be described, will produce better targets than has been possible with any bullet heretofore produced, will not tear the target but will cut a round hole therein, will be self-centering in the bore of a gun barrel should it happen to be loose in the cartridge shell and will effectually clean the grooves of the bore and keep them clean. With these and other objects in view, I have devised the novel target bullet which I will now describe, referring to the accompanying drawings forming a part of this specification, and using reference characters to indicate the several parts.

Figure 1 is an elevation of my novel bullet; Fig. 2 a longitudinal section thereof, also showing an additional lubricating groove; Fig. 3 a front end elevation of the bullet after leaving the gun barrel; Fig. 4 a longitudinal section of the rear end of a gun barrel showing a cartridge with my novel bullet in place therein; Fig. 5 a longitudinal section of a portion of the bore of a gun barrel showing the bullet during its passage therethrough, and Fig. 6 is an illustration of a target which has been hit by an ordinary bullet and also by my novel target bullet.

10 denotes a gun barrel, 11 the grooves of the bore, 12 the lands, 25 the chamber, 13 the shell of the cartridge and 14 my novel bullet which is made of lead or an alloy of lead and is not jacketed. My novel bullet comprises a heel 15, a body portion 16 and a tip 17. The length of my novel bullet may vary from one and one-half to two and one-half times the caliber as variations from a length of twice the caliber, which I find very satisfactory in use. The body of the bullet is cylindrical and is provided with the usual lubricating grooves 18. The heel is of reduced diameter and may or may not be rounded at its rear end. The tip 55 tapers slightly in a straight line from its

intersection with the body to the forward end, which is flat across, as at 19, and is provided with a central recess or cavity 20 having an inclined wall. The depth of the recess is not of the essence of the invention 60 but depends upon the length and diameter of the bullet and is so proportioned as to give perfect balance to the bullet.

An essential feature of the bullet is that it is flat across its forward end as distinguished from having any point whatever, the thickness, however, of the wall at the forward end is immaterial, it being simply necessary to insure sufficient stiffness to prevent deformation of the bullet in handling. The tip may or may not be provided with an additional lubricating groove 21, as shown in Fig. 2.

Another essential feature of my novel bullet is that the diameter at the forward end of the tip corresponds substantially with the diameter of the gun barrel from which it is to be fired, at the tops of the lands, and the diameter at the rear end of the tip corresponds substantially with the 75 diameter of the gun barrel at the bottom of the grooves, so that while the shell and the body of the bullet fit the chamber with merely a close fit as usual, pressure must be applied to the rear end of the cartridge 85 to force the tip of the bullet into the bore. The bullet is easily seated, however, owing to the fact that it is relatively soft. The effect of forcing the tip of the bullet into the bore is to cause the lands of the bore 90 to form corresponding grooves in the bullet, which are indicated by 22 in Fig. 4. When the bullet is fired, the effect of the resistance of the air owing to the recess in the tip is to expand the tip outward so that still 95 deeper grooves are formed in the bullet which are indicated by 23 in Fig. 5 and which correspond with the lands of the bore, leaving ribs 24 between the grooves 23 which correspond with the grooves of 100 the bore and fill said grooves and also leaving the bullet supported in the barrel from end to end so that deflection of the bullet (keyholing, as it is called) is avoided. These ribs upon the bullet effectually clean the 105 grooves of the bore and keep them clean so long as my novel bullets are used, see Fig. 5, in which the dirt in the grooves of the bore, which is scraped up and forced out by my novel bullet, is indicated by 26. An- 110

other important advantage resulting from the taper of the tip in connection with its slightly greater diameter than the bore of the gun barrel from which it is to be fired 5 is to insure that it will seat itself centrally in the bore, even though it may be loose in the cartridge shell, a condition that frequently happens in small caliber cartridges.

The vitally important result, however, 10 cured by my novel bullet is its extreme accuracy in short range shooting. My novel bullet does not tear a paper target but cuts or drills a round hole in it of appreciably greater diameter than the caliber. The 15 reason for this will be readily understood from Fig. 3, which see in connection with Fig. 6. It must be borne in mind that owing to its taper and its greater diameter than the lands of the bore, the bullet is sure to 20 be seated centrally in the bore, that is the axis of the bullet will coincide with the axis of the bore and that owing to the fact that the bullet is flat across its forward end and is provided with a cavity or recess, the 25 resistance of the air will expand the forward end of the bullet into the grooves of the bore forming ribs which not only scrape the grooves of the bore rendering it unnecessary to stop to clean it, but also increase the 30 active or operative diameter of the bullet when it strikes the target, so that there can be no tearing of the target but in fact a round hole is drilled or cut in the target by the rapidly rotating bullet. In fact it is frequent 35 with my novel bullet to cut sharply two rings of a standard target which can be done with no other bullet known to the trade.

In Fig. 6, which represents an actual target, 40 27 indicates a hole made by an ordinary bullet. In practice the hole is torn, the paper of the target being punched aside but not cut out and removed so that the hole partly fills the instant the bullet has 45 passed. 28 indicates a hole cut by one of my novel bullets of the same caliber, its center being equi-distant with the center of hole 27 from the center of the target. Hit

27 will score nine while hit 28 will score ten. 29 indicates a hole made by one of my novel bullets and cutting two circles of the target, but scoring ten. It will be noted that the use of my novel bullets avoids all 55 questions regarding doubtful shots in official targets.

Having thus described my invention I claim:

1. A target bullet comprising a body portion adapted to fit the chamber of the gun barrel from which it is to be fired and a 60 tip tapering in a straight line from the body portion to the forward end which is flat across and is provided with a central recess having a tapering wall, the diameter at the forward end of the tip corresponding substantially with the diameter of the gun barrel at the tops of the lands and the diameter at the rear end of the tip corresponding substantially with the diameter of the gun barrel at the bottom of the grooves. 65

2. A target bullet having a length approximately twice its caliber and comprising a body portion adapted to fit the chamber of a gun barrel and a tip tapering in a straight line from the body portion to the 70 forward end, said tip being flat across its forward end and provided with a central recess having a tapering wall, the diameter at the forward end of the tip corresponding substantially with the diameter of the gun 75 barrel at the tops of the lands and the diameter at the rear end of the tip corresponding substantially with the diameter of the gun barrel at the bottom of the grooves, whereby the bullet is made self-centering 80 in the gun barrel and is caused to cut a round hole in a paper target the full diameter of the barrel at the bottom of the 85 grooves.

In testimony whereof I affix my signature in presence of two witnesses.

ALBERT B. GULLY.
